UNITED STATES PATENT OFFICE.

MAGGY BESANÇON DE WAGNER, OF PARIS, FRANCE, ASSIGNOR TO LENTHERIC, INCORPORATED, OF NEW YORK, N. Y., A CORPORATION OF NEW YORK.

DESIGN FOR A BOTTLE.

Application filed January 12, 1929. Serial No. 29,581. Term of patent 14 years.

To all whom it may concern:

Be it known that I, MAGGY BESANÇON DE WAGNER, a citizen of the Republic of France, residing at Paris, France, 26, Avenue du Bois, have invented a new, original, and ornamental Design for a Bottle, of which the following is a specification, reference being had to the accompanying drawing forming a part thereof.

In the drawing,
Fig. 1 is a perspective front view.
Fig. 2 is a side view.
Fig. 3 is a top view.

I claim:

The ornamental design for a bottle substantially as shown.

MAGGY BESANÇON DE WAGNER.
